Application February 18, 1947, Serial No. 729,372

9 Claims. (Cl. 68—23)

1

This invention relates to the elimination of vibration in rotating and oscillating machinery, with particular application to laundering machines of the character disclosed in my copending applications, Serial No. 526,154, filed March 13, 1944, now Patent No. 2,520,366, Serial No. 619,849, filed October 2, 1945, and Serial No. 671,779, filed May 23, 1946.

These laundering machines incorporate a container in which articles are first washed and are then dried by centrifugal action. During the washing operation, the container is given a rapid oscillating, jiggling, or wobbling motion, the consequent reversals of motion tending to establish vibration. During the centrifugal drying operation, unbalance of the material in the rotating container may also cause vibration.

The vibratory tendencies of the machine during both phases of operation must be inhibited to provide an acceptable machine.

The principal object of this invention is to prevent, absorb, nullify, or counteract vibration in machines in which oscillating or unbalanced rotating parts generate forces tending to cause vibration, with particular reference to washing machines of the type disclosed herein and in the abovementioned copending applications.

The manner in which this and other objects and advantages are accomplished may be more completely understood by consideration of the description herein of preferred modes of application of the principles of the invention.

Referring to the drawings:

Figure 1 is a vertical sectional view of a washing machine incorporating one embodiment of the invention, the section being taken on a plane passing through the central axis of the machine;

Figure 2 is an enlarged partial vertical section taken on the plane indicated by the line 2—2 in Fig. 3, showing principally the vibration eliminator;

Figure 3 is a horizontal section taken on the plane indicated by the line 3—3 in Fig. 2;

Figure 4 is a partial plan view illustrating the flexible mounting for the moving parts of the machine;

Figure 5 is a vertical section taken on the plane indicated by the line 5—5 in Fig. 4;

Figure 6 is a vertical axial section of a washing machine incorporating a second embodiment of the invention, taken on the plane indicated by the line 6—6 in Fig. 7; and

Figure 7 is a horizontal section taken on the plane indicated by the line 7—7 in Fig. 6.

The washing machine comprises a casing 11, Fig. 1, preferably rectangular in cross section, within which is fixed a cylindrical tub 12. The articles to be washed are placed in a more or less toroidal container 13, which is supported within the tub by a pedestal 14. Transmission of vibrations from the container 13 to the frame of the

2

machine may be lessened by a slightly resilient support for the pedestal 14 comprising four radial arms 16 (Figs. 1, 4, and 5) bolted to a flange 17 welded to the pedestal at the base thereof. The outer ends of the arms are secured to the four corners of a square plate 18 by nuts 19 on eyebolts 21 passing through the arms and threaded into the plate. The plate 18 may be leveled by adjustment of the eyebolts therein. The eyebolts are suspended by short closed coil springs 22 engaged in the eyes thereof, and in eyes 23 of brackets 24 bolted into the corners of the casing 11. Rubber bushings 25 having grooved margins are fitted into the eyes of the bolts 21 and brackets 24 to eliminate any tendency of the springs 22 to chatter in the eyes.

The portion of the casing which supports the weight of the rotating mechanism is strengthened by corner stiffeners 26 of appropriate gauge welded into the casing. The lower edges of the stiffeners 26 are welded to an angle iron frame 27 welded to the lower portion of the casing, and constituting therewith a channel section.

Preferably, the casing is supported upon four adjustable feet 28 (Fig. 5) each consisting of a body 29 tapped for the reception of a cap screw 31 fitted with a jam nut 32. The body 29 may be welded to the bottom frame 27.

Relative movement between the pedestal 14 and the tub 12 is accommodated by a flexible boot 33 (Fig. 1) of rubber or the like, secured at its upper end to the pedestal by screws 34, and at its lower end to a flange 36 in the bottom of the tub circumjacent the pedestal by rivets or bolts 37.

Any vibration in the machine would normally originate in the container 13 and be transmitted by the pedestal 14. A vibration-eliminating device 40, which will be described later, nullifies substantially all vibration. Isolation of the pedestal from the tub and floor-supported frame prevents transmission of residual vibrations thereto. This isolation is accomplished by means of the boot 33, and the suspension by the springs 22. It should be noted that the springs are primarily suspension links permitting lateral vibration of the plate 18 and the mechanisms supported thereby without transmitting the vibrations to the frame, and thus preventing any tendency of the machine to "crawl" across the floor. This suspension may, however, be omitted since substantially all vibration is damped.

The operation of the container 13 is fully explained in the abovementioned copending applications, but will be described briefly herein in the interest of fuller understanding of the vibration problem to the solution of which the instant invention is directed. A motor 41 (Fig. 1) mounted on the plate 18 drives a hollow shaft 42 within the pedestal by means of a belt 43 and pulleys 44 and 45. A flange 46 at the upper end

of the hollow drive shaft 42 mounts a ball bearing 47 in slightly skewed relation to the shaft. The inner race of the bearing supports the container 13, the axis of which coincides with the axis of the bearing. A control shaft 48 within the hollow drive shaft 42 is coupled to the container 13 by means of a universal joint 49, and is fitted at its lower end with a brake drum 51. The control shaft may be restrained against rotation by a brake band 52, or may be coupled to the drive shaft for rotation therewith by clutch devices 53 engaging the inner surface of the pulley 45.

When the drive shaft is rotated and the control shaft is braked, for the washing operation, the container 13 does not rotate, but has an oscillating motion which may be described as the resultant of two simple harmonic oscillations, in quadrature of phase, about mutually perpendicular horizontal axes.

When the machine is operated as a centrifuge, the drive and control shafts are coupled together, and the motion of the container is a simple rotation about a vertical axis. Vibration inducing forces may be set up in this case by unbalance of the contents of the container, and also by the lack of dynamic balance of the container due to its skewed relation to the axis of rotation.

Two species of a type of vibration-absorbing device are disclosed herein. Both are based upon the provision of elastically supported masses, the mass-elastic systems being tuned to vibrate at a frequency corresponding to the rotational frequency of the drive shaft 42.

The form of vibration absorber identified generally by the reference number 40 in Fig. 1 comprises a sleeve 61 (Figs. 2 and 3) dimensioned internally for a sliding fit on the pedestal 14 and locked in position by a set screw 62. The sleeve is formed with four equi-spaced projections 63 with grooves 64 tangent to the outer surface of the sleeve for the reception of the lower edges of four semi-circular flat springs 65 arranged spirally outward from the sleeve. A cap 66 retained on the upper end of the sleeve by four machine screws 67 compressively engages the upper edges of the springs, and is formed with partial flanges 68 for their retention. Bolts 69 passed through holes in the outer ends of the springs retain resilient bushings 70 of a well-known type, the marginal flanges of which embrace the edges of holes in angle brackets 72. The four angle brackets are bolted to the underside of a ring 73, from which four weights 74 are suspended intermediate the brackets 72 by bolts 75. It will be apparent that other numbers of springs and weights than four may be employed, and that the weights 74 may be omitted if the ring 73 be made sufficiently heavy.

It will be apparent that, by virtue of the manner in which the weights 74 are suspended, they may vibrate horizontally in any direction with respect to the pedestal 14 with the same fundamental frequency of vibration. The stiffness of the springs and the mass of the unit are so related that the fundamental frequency of vibration corresponds to the rotational speed of the drive shaft 42. Thus transverse vibration of the pedestal occasioned by unbalance of material being centrifuged is absorbed.

It has also been found that the unit 40 will absorb the vibrations caused by the complex oscillating motion of the machine during washing. The reactions to the driving of the container 13 in its washing motion include a couple tending to

lift the side of the machine where it rests upon a floor or other support, the lifting tendency traveling about the supporting base at the same rate at which the hollow shaft 42 is rotated. A component of the motion which tends to result from this couple is transverse to the column axis at the point of support of the springs 65 and the device 40 is thereby set in motion with sufficient amplitude to counteract the couple. Since the shaft 42 is driven at the same speed for both washing and extracting, the vibration absorbing device is properly tuned for both types of vibrations.

In either mode of operation of the machine, therefore, the vibrations of the pedestal are quenched by the reactions of the resonant induced vibrations of the device 40.

A modified form of vibration-absorbing device employing the principles just considered is illustrated in Figs. 6 and 7. The washing machine is the same, so it need not be described. The vibration eliminator is mounted on the freely suspended base plate 18 in the second form. The principal elastic members are vertical rods 80, preferably three in number, fixed in any desired manner in sockets 81 bolted to the base plate 18 in equally-spaced relation with respect to the pedestal 14. The arms 16 may be cut away slightly, as illustrated in Fig. 7, to provide clearance for the rods 80.

The rods 80 pass through flanged apertures 82 in the bottom of the tub 12, and are fitted with flexible boots 83 in the same manner as the pedestal 14 to retain the fluid in the tub and isolate the vibrating rods from the tub.

The upper ends of the rods are formed with a reduced portion 84 on which flexible bushings 85 are retained by nuts 86. The bushings are formed with a grooved periphery which receives the inner margin of an offset annular member 87. The members 87 are bolted to a ring 88 provided with apertures 89 for clearance of the rods. Weights 91 are suspended from the ring intermediate the rods by bolts 92.

The mass comprised by the weights 91 and the parts rigidly associated therewith may vibrate in any horizontal direction by flexion of the rods 80. The mass may also oscillate to a limited extent about horizontal axes through its center of mass by flexion of the bushings 85. Vibration of the pedestal 14 due to the oscillating or rotary motion of the container as previously described, appears in the plate 18 at least in part as horizontal vibration, and is damped by resonant vibrations of the mass-elastic system of the rods, ring, and weights.

It should be noted that the flexible suspension of the working parts of the machine, and their isolation from the casing and frame, are valuable factors in the success of the invention. The principles of the invention are to concentrate vibration in structures designed to vibrate freely, thus minimizing vibration in the working parts of the machine, and to minimize transmission of residual vibrations to the fixed parts of the machine by the flexible mounting. However, the flexible mounting may be omitted where some slight vibration of the frame is permissible.

It will be apparent that various forms of flexible membranes or other devices to preserve the water-tightness of the bottom of the tank and permit free movement of the pedestal and vibrating rods relative thereto. The term "flexible

"boot" in the claims is intended to be generic to all such flexible connections.

Although the foregoing description is necessarily of a detailed character, in order that the invention may be completely set forth, it is to be understood that the specific terminology is not intended to be restrictive or confining, and that various rearrangements of parts and modifications of detail may be resorted to without departing from the scope or spirit of the invention as herein claimed.

I claim:

1. In a laundering machine, a frame, a subframe including a base and a pedestal extending upwardly from the base, a container for articles being processed mounted on the pedestal on an axis inclined with respect to the axis of the pedestal, means on the subframe for imparting rotary and wobbling motions to the container for centrifugal extraction and for washing respectively, vibration-damping means on the subframe, and means for supporting the subframe from the frame comprising a plurality of links freely articulated to the subframe at the outer periphery thereof and the base, the links normally being substantially vertical, each link consisting of a closed-coil spring.

2. In a machine, a subframe comprising a base and a member extending upwardly from the base, a rotor mounted on the top of said member, means on the subframe for imparting rotary and oscillating motions to the rotor, and means for damping vibrations of the subframe resulting from movement of the rotor comprising a body surrounding the member and having its center of mass substantially coincident with a line joining the centers of mass of the base and rotor, a plurality of elastic members having one end thereof coupled to the member and the other end free to vibrate, and flexible means coupling the free ends of the elastic members to the body.

3. In a machine, a subframe comprising a base and a member extending upwardly from the base, a rotor mounted on the member in vertically spaced relation to the base, means on the subframe for imparting rotary and oscillating motions to the rotor, and means for damping vibrations of the subframe resulting from movement of the rotor comprising a body surrounding the member and having its center of mass substantially coincident with a line joining the centers of mass of the base and rotor, a plurality of elastic members having one end thereof coupled to the base and the other end free to vibrate, and flexible means coupling the free ends of the elastic members to the body.

4. In a laundering machine, a frame, a tub thereon, a subframe, a pedestal extending from the subframe upwardly into the tub, a flexible boot between the pedestal and tub, a container atop the pedestal, means for imparting motion to the container, and vibration-damping means mounted on the pedestal within the tub comprising a ring disposed around the pedestal, a plurality of flat springs attached to the pedestal and extending therefrom, and means connecting the springs to the ring.

5. In a laundering machine, a frame, a tub thereon, a subframe flexibly mounted in the frame, a pedestal extending from the subframe into the tub, a flexible boot between the pedestal and tub, a container atop the pedestal, means for imparting motion to the container, and vibration-damping means mounted on the pedestal within the tub comprising a ring disposed

around the pedestal, a plurality of flat springs fixed to the pedestal and extending spirally therefrom, and resilient means connecting the springs to the ring.

5. In a laundering machine, a frame, a tub thereon, a subframe freely suspended from the frame below the tub, a pedestal extending from the subframe into the tub, a flexible boot between the pedestal and tub, a container atop the pedestal, means for imparting rotary and oscillating motion to the container, and vibration-damping means mounted on the pedestal within the tub comprising a ring disposed around the pedestal and a plurality of flat springs fixed to the pedestal, extending spirally therefrom, and connected to the ring.

6. In a laundering machine, a frame, a tub thereon, a subframe freely suspended from the frame below the tub, a pedestal extending from the subframe into the tub, a flexible boot between the pedestal and tub, a container atop the pedestal, means for imparting rotary and oscillating motion to the container, and vibration-damping means mounted on the pedestal adjacent the container comprising a ring disposed around the pedestal, a plurality of flat springs fixed to the pedestal and extending spirally therefrom, and resilient means connecting the springs to the ring.

7. In a laundering machine, a frame, a tub thereon, a subframe freely suspended from the frame below the tub, a pedestal extending from the subframe into the tub, a flexible boot between the pedestal and tub, a container atop the pedestal, means for imparting rotary and oscillating motion to the container, and vibration-damping means mounted on the pedestal adjacent the container comprising a ring disposed around the pedestal, a plurality of flat springs fixed to the pedestal and extending spirally therefrom, and resilient means connecting the springs to the ring.

8. In a laundering machine, a frame, a tub

thereon, a subframe freely suspended from the frame below the tub, a pedestal extending from the subframe into the tub, a flexible boot between

the pedestal and tub, a container atop the pedestal, means for imparting rotary and oscillating

motion to the container, and vibration-damp-

ing means mounted on the pedestal within the

tub comprising a ring disposed around the ped-

estal, a plurality of flat springs fixed to the

pedestal and extending spirally therefrom, and

resilient means connecting the springs to the

ring.

9. In a laundering machine, a frame, a tub thereon, a subframe freely suspended from the frame below the tub, a pedestal extending from the subframe into the tub, a flexible boot between the pedestal and tub, a container atop the pedestal, means for imparting motion to the container, and vibration-damping means mounted on the pedestal within the tub comprising a ring disposed around the pedestal, weights rigidly sus-

pended from the ring, a plurality of flat springs

fixed to the pedestal and extending spirally

therefrom, and resilient means connecting the

springs to the ring.
